P. J. LINDGREN.

FAUCET,

APPLICATION FILED JAN. 31, 1912.

1,075,483.

Patented Oct. 14, 1913.

UNITED STATES PATENT OFFICE.

PETER J. LINDGREN, OF DENVER, COLORADO.

FAUCET.

1,075,483.

Specification of Letters Patent. Patented Oct. 14, 1913.

Application filed January 31, 1912. Serial No. 674,443.

To all whom it may concern:

Be it known that I, PETER J. LINDGREN, a citizen of the United States, residing at Denver, in the county of Denver and State of Colorado, have invented certain new and useful Improvements in Faucets, of which the following is a specification.

My invention relates to improvements in faucets and its object resides in providing in combination with a faucet, a bubbling drinking cup, the admission of fluid to which is governed by the same valve which controls the flow of water to the spout of the faucet. With this purpose in view, I substitute for the valve handle of the ordinary faucet, a tube which carries a bubbling cup in communication with its interior and I construct the body of the faucet and the valve seated therein, with correlative ports and passages whereby an adjustment of the valve to determinate positions relative to the faucet body, will result in directing the flow of water either into the bubbling cup, or through the faucet spout, or will stop the supply of fluid to both the cup and the spout or will drain the cup through the spout. In addition to these features I have provided means for controlling the flow of water from the tubular handle to the cup and I have constructed the latter so as to insure a steady, uniform flow of water through its outlet.

While my invention may be effectively applied to faucets of different construction it is particularly adapted for use on basin cocks and it has been shown as applied to a fixture of this type in the accompanying drawings in the various views of which like parts are similarly designated and in which—

Figure 1 represents a vertical sectional view of a basin-cock in which my invention is embodied, Fig. 2, a section taken along the line 2—2, Fig. 1, Fig. 3, a transverse section along the line 3—3, Fig. 1, showing the position of the faucet-valve when the water is discharged through the faucet-spout, and, Fig. 4, a similar view with the valve in the position in which the contents of the bubbling cup are discharged through the spout.

Referring more specifically to the drawings, the numeral 2 designates the faucet-body which as usual is constructed to be secured upon a suitable support 3 by the application of a nut 4 and to connect at its lower end with a conduit leading to a supply of water. An axial bore 5 in the body 2 terminates in the conoidal valve-chamber 6 which communi-

cates with the interior of the faucet-spout 7. A valve 8 rotatably fitted in the valve chamber is maintained in constant engagement with the surface thereof by means of a spring 9 and its threaded stem 10 which projects through an opening in the upper portion of the body 2 is by means of an elbow 12, connected with a tubular rod 13 which at its outer extremity carries the bubbling cup 15 and which together with a therewith axially alined extension 14, screwed into the basic body of the said cup, constitutes the handle by manipulation of which the valve is turned about its vertical axis to any one of the positions hereinbefore referred to.

The bubbling cup 15 is composed of an axially bored body member 16 which connects with the tube 13 and whose upper exteriorly threaded portion projects into the globular cup-member 17 which being screwed onto the said portion, engages a shoulder at the lower end of the same. The axial bore 18 of the body member of the cup communicates with the interior of the cup-member by means of a plurality of transverse passages 19 and the flow through these passages is controlled by means of a screw-valve 20 which vertically adjustably projects into the correspondingly threaded end of the bore 18.

The cup-member 17 has in axial alinement with the bore of the body-member upon which it is supported, an outlet formed by an inwardly extending cylindrical flange 21 which in the operation of the device, serves to render the flow of water through the said outlet steady and uniform by compelling the fluid which enters the cup-member through the transverse passages 19 to come to a comparative condition of rest in the recess formed around it, before being discharged through the same.

The valve 8 is provided with two separate axial passages 22 and 23 which are respectively in continuous communication with the bore 5 of the faucet-body and with the interior of the tubular rod 13. The passage 23 connects with ports 24 and 25 located at opposite sides in the exterior surface of the valve and the passage 22 is in communication with an elongated port 26 disposed in the same surface in vertical alinement with the port 24 and partially in a plane transverse to the axis of rotation of the valve with the port 25 which is disposed to register with the orifice 28 of the spout 7

in the valve-chamber. The latter is furthermore provided in its interior surface with a longitudinally extending groove or recess 27 which in the operation of the device 5 serves as a by-pass to establish a communication between the ports 26 and 24 and through them between the passages 22 and 23 in the valve 8.

When the valve is in the position shown 10 in Figs. 1 and 2, its handle is in its central position over the spout 7, the communication between the passages 22 and 23 is established by means of the by-pass, as above explained, and the orifice of the spout 7 is 15 closed so that the water entering the bore 5 of the faucet-body will flow only into and out of the bubbling-cup 15. An adjustment of the valve-handle to either the right or the left will cause the flow of water to 20 the cup to gradually diminish and eventually stop; by turning the handle farther to the right until it is at an angle of about ninety degrees to its former position, as is shown in Fig. 3 of the drawings, the port 25 26 is brought in communication with the orifice 28 of the spout and the ports connected with the upper passage 23 are closed with the result that the water entering the faucet-body is discharged only through the 30 spout 7, and by turning the handle farther to the left until it has assumed a position at approximately ninety degrees to its central position, as is illustrated in Fig. 4, the port 25 is brought in register with the 35 orifice 28 of the spout and the cup is in consequence, drained through the latter.

It will be observed that, inasmuch as 40 faucets are made of many different forms and constructions, variations in the form and arrangement of the parts included in my

invention must necessarily be resorted to, to render it applicable to faucets which in form or construction differ from that shown in the drawings and hereinbefore described, and I wish it understood that such variations may be availed of within the spirit 45 of my invention.

Having thus described my invention what I claim and desire to secure by Letters-Patent is:

1. A faucet comprising a body having an inlet and an outlet, a valve in said body, and a bubbling cup, said valve having, internally, separate passages respectively in communication with said inlet and said cup, and in its exterior surface, ports connecting with the respective passages, one of said ports being disposed to register with said outlet, and the said body having a by-pass for establishing communication between said ports.

2. A faucet comprising a body having an inlet and an outlet, a valve in said body, and a bubbling cup, said valve having internally, separate passages respectively in communication with said inlet and said cup, and in its exterior surface, a pair of ports connected with one of said passages and a third port connected with the other passage, the said third port and one of said pair of ports being disposed to register with said outlet, and the said body having a by-pass for establishing communication between said third port and the other port of said pair.

In testimony whereof I have affixed my 75 signature in presence of two witnesses.

PETER J. LINDGREN.
